UNITED STATES PATENT OFFICE.

REUBEN L. SKINNER, OF CULLISON, KANSAS.

SCOOP APRON.

Application filed January 23, 1924. Serial No. 687,998.

To all whom it may concern:

Be it known that I, REUBEN L. SKINNER, a citizen of the United States, residing at Cullison, in the county of Pratt and State 5 of Kansas, have invented a new and useful Scoop Apron, of which the following is a specification.

This invention relates to scoop aprons for use in transferring grain from a wagon to 10 a bin or from a car to a wagon.

The object of the invention is to provide an apron of this character constructed so as to be adjusted for use in connection with vehicles of different widths the width or 15 spread of the apron being automatically adjustable and retained tight by a take-up device.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed without departing from the spirit of the invention.

In the accompanying drawings:—

Figure 1 represents a perspective view of 30 an apron constructed in accordance with this invention shown open ready for use.

Fig. 2 is a transverse section taken on the line 2—2 of Fig. 3.

Fig. 3 is a detail longitudinal section 35 through one end of the casing which houses the apron; and

Fig. 4 is a detail sectional view showing the means for connecting the apron to the roller.

In the embodiment illustrated a casing 1 is shown composed of telescoping sections 2 and 3 here shown cylindrical and split longitudinally with outwardly extending lips 4 arranged on opposite sides of the slit 40 or split portion to form guides for the apron 10. This apron is made of canvas or other suitable flexible material and one end detachably secured to a longitudinally adjustable roller 15 by means now to be described. The roller is made in telescopically engaged sections 16 and 17 which are longitudinally slotted throughout their length as shown at 18 the slot in one section registering 45 with that in the other to receive the edge of the apron 10 which is made of a width greater than the length of the roller 50 55 60 65 70 75 80 85 90 95 100 105 110

and the side edges thereof folded inward as shown at 14 in Fig. 1 to provide for increasing the width of the apron when desired. The roller sections at their outer ends are provided with slots 19 which parallel the slots 18 and communicate at their outer ends by transverse slots 20 which form tongues 21 fixed at their free ends to the roller and around which the folded portions 14 of the apron are designed to be arranged as shown in Fig. 4. The inner edges of the folded portions 14 are connected by an elastic connector preferably in the form of a rubber band or strap 22 which holds the apron yieldably and detachably connected with the roller and permits said apron to automatically widen on the lengthening of the roller the folded portions 14 providing for this.

The sections 2 and 3 of the casing 1 are equipped with hooks 5 adapted to be engaged with the tail board or side of a wagon or with any other support in connection with which the apron is to be used. These sections are closed at their outer ends one being slotted as shown at 6 for the passage of the angular end of the roller pindle 7 the other section end having the round end of the pindle loosely mounted therein and secured by any suitable means.

A roller locking device is carried by the outer end of section 2 and is made in the form of a hook 8 the bill of which is arranged on the outer face of the casing end and its shank extended loosely through said end and provided with a head 9 between which and the casing end is a spring 23 which bears against said head to cause it to yieldably hold the roller 15 against turning when said head is engaged with one of the cams 24 on the end of the roller. This roller lock is intended to prevent the spring from turning the roller when the apron has been pulled out to its extreme length or for any other purpose to hold it in this position during the lengthening of the roller and the casing as well as the widening of the apron when the device is to be used in connection with wider doors. The width or spread of the apron is automatically held tight by the take-up device, in the form of the rubber strap 22 which connects the edges of the apron portions 14. While a rubber strap is described and shown for this purpose it is to be understood that a coiled spring or any other elastic device may be used.

The free end of the apron 10 is equipped with a telescoping rod 11 at the outer ends of the sections of which are rings or loops 12 adapted to be engaged with hooks or 5 other devices on the bin or car in connection with which the apron is to be used.

It is understood that this apron is to be used as a scoop apron to prevent spilling or wasting of grain when being transferred 10 from a wagon or a bin or from a car to a wagon or vice versa.

The angular end of pintle 7 of the roller is shown extended through the end wall of 15 the casing and secured by a cotter pin 13 although obviously it may be secured by any other suitable means.

The roller 15 is controlled by a spring in the manner of the ordinary shade roller so that the apron may be pulled out and wound 20 up on the roller in the manner of a curtain or shade.

I claim:—

1. A scoop apron comprising a casing having a longitudinal slot therein, a spring 25 roller mounted to turn in said casing, an apron carried by said roller and operable through the slot in the casing, a cam on said roller end, a spring pressed catch carried by said casing and located in the path of 30 said cam, said catch projecting through the casing and having a finger grip for operating it to engage the cam and lock the roller against turning.

2. A scoop apron comprising a casing having a longitudinal slot therein with outwardly extending lips to form guides for the apron in connection with which it is to be used, a hollow spring roller mounted to turn in said casing, said roller being longitudinally slotted to receive the apron and having tongues at the ends thereof, an apron having its edges folded inwardly to receive said tongues, and an elastic connector within the roller engaged with the edges of the apron, to hold the apron taut and permit it to be changed in width. 35

3. A scoop apron comprising a hollow roller composed of telescopically engaged sections, said sections having registering slots to receive the apron in connection with which it is to be used each section having at its outer end a slot paralleling the first mentioned slot, said slots communicating at their outer ends to form tongues, and an apron having its side edges folded to receive the tongues, and an elastic element connecting the edges of the apron to hold it taut and permit the width thereof to be adjusted. 40

In testimony that I claim the foregoing as 45 my own, I have hereto affixed my signature in the presence of two witnesses.

REUBEN L. SKINNER.
